(57) **CLAIM**

The ornamental design for a floor drain grate as shown.

DESCRIPTION

FIG. 1 is a top front right perspective view of the floor drain grate showing my new design.

FIG. 2 is a top back right perspective view thereof.

FIG. 3 is a top view thereof.

FIG. 4 is a front view thereof.

FIG. 5 is a right side view thereof.

FIG. 6 is a back view thereof; and,

FIG. 7 is a left side view thereof.

The dashed broken lines depict portions of the floor drain grate that form no part of the claim.
